UNITED STATES PATENT OFFICE.

ELBERT ALLEN HAWKINS, OF ROCHESTER, NEW YORK.

BLACKING-GUARD.

No. 820,493.

Specification of Letters Patent.

Patented May 15, 1906.

Application filed April 28, 1905. Serial No. 257,932.

To all whom it may concern:

Be it known that I, ELBERT ALLEN HAWKINS, a citizen of the United States, residing at Rochester, in the county of Monroe and State of New York, have invented a new and Improved Blacking-Guard, of which the following is a specification.

This invention relates to means for preventing the soiling of the hose in the process of applying the blacking to the shoe and in polishing the same, the purpose being to overcome the difficulty which has heretofore been experienced in applying blacking to shoes, especially low shoes, and polishing them, in that it has been necessary to exercise great care to prevent the soiling of the hose by the contact therewith of the brush used in applying the blacking or in polishing the same.

The invention consists in guards, preferably two in number, of suitably flexible and elastic material adapted to readily conform to the foot of the user upon being inserted between the shoe and the foot with the hose thereon.

After devising a number of forms I have found that such guard may consist conveniently of two pieces to be used in a shoe, when properly conformed and of suitable material, so as to fully protect the hose, and at the same time such pieces may be adjustable over a considerable range of difference in the sizes of the shoe and foot therein.

It is preferable, of course, that such guards be composed of some material which will permit of their being readily cleansed or washed. This is an important feature in order that the blacking, which has accumulated on the guards in blacking the shoes in one operation, may be removed so that it will not soil the inside of the shoe when the guards are used the next time. I have found that celluloid, flexible fiber, or a good grade of press-board may be used. These guards I prefer to so form that their overlapping portions, at about the center of the opening in the shoe for the ankle, shall be considerably wider than at the instep and at the back of the ankle, as the guards at these last-mentioned points make sharper curves, as will at once be understood, than at the sides, where the ends of such guards overlap.

The accompanying drawings, illustrating my invention, are as follows:

Figure 1 is a view of a low shoe with my

guard in place. Fig. 2 is a developed view of one portion of the guard, while Fig. 3 is a developed view of the other portion.

Similar letters refer to similar parts throughout the several views.

As seen in the drawings, my blacking-guard comprises two portions A and B, each of such an irregular outline that when inserted within the upper edge of the shoe C the upper edge of the guard will project above the top of the shoe at all points and in that way form a perfect protection for the hose. The portion A is designed to go in the front part of the shoe, while the portion B is designed for the back portion of the shoe, and the ends of these two portions are arranged to overlap, and in that way when used on a small shoe they will extend by or overlap one another quite a distance, but when used on larger shoes these ends will overlap only a sufficient distance to provide the necessary protection for the hose.

It will at once be seen that the guards when conformed and used in the manner above described are readily adaptable to use with shoes varying in size over a considerable range and afford ample protection for the hose, and that when composed of suitable material, such as indicated, they may be readily washed after each use, so that they may not soil the hose or the inside of the shoe when next used.

Attention is called to the fact that the material of which the guards are composed should possess such a degree of flexibility as to readily conform to the shape of the foot and shoe of the user in each case, and such material should possess such a degree of elasticity and rigidity as to keep the guards firmly in contact with the inside of the shoe against the pressure exerted in blacking and polishing the same to prevent superfluous blacking getting inside the shoe.

What I claim is—

1. As a new article of manufacture, a blacking-guard consisting of two pieces of suitably flexible and elastic material adapted to be inserted within the upper edge of the shoe of the user, one of such pieces adapted to fit around the instep and the other around the back of the ankle, the free ends of such pieces overlapping more or less according to the size of the shoe and foot therein.

2. As a new article of manufacture, a blacking-guard consisting of two pieces of suitably flexible and elastic material adapted

to be inserted within the upper edge of the shoe of the user, one of such pieces adapted to fit around the instep and the other around the back of the ankle, and the free ends of such pieces overlapping more or less according to the size of the shoe and foot therein, such pieces widened and rounded at their free ends.

3. As a new article of manufacture, a blacking-guard consisting of two pieces of suitably flexible and elastic material adapted to be inserted within the upper edge of the shoe of the user, one of such pieces adapted to fit around the instep and the other around the back of the ankle, the free ends of such pieces overlapping more or less according to the size of the shoe and foot therein; such

free and overlapping ends widened out and having rounded corners.

4. As a new article of manufacture a blacking-guard of suitably flexible and elastic material adapted to be inserted within the upper edge of the shoe of the user and extending above the upper edge of the shoe and adapted to protect the stocking therein while exposing the entire outer surface of the upper edge of the shoe, such guard having free ends arranged to overlap more or less according to the size of the shoe and foot therein. 20 25

ELBERT ALLEN HAWKINS.
